US0D1034690S

(12) **United States Design Patent** (10) **Patent No.:** **US D1,034,690 S**
(45) **Date of Patent:** **** Jul. 9, 2024**

(54) **DISPLAY SCREEN OR PORTION THEREOF WITH GRAPHICAL USER INTERFACE**

(71) Applicant: **HUAWEI TECHNOLOGIES CO., LTD.**, Guangdong (CN)

(72) Inventors: **Lina Tao**, Shenzhen (CN); **Anqi Liu**, Shenzhen (CN); **Fei Ye**, Wuhan (CN); **Yufeng Huang**, Shanghai (CN)

(73) Assignee: **HUAWEI TECHNOLOGIES CO., LTD.**, Shenzhen (CN)

(**) Term: **15 Years**

(21) Appl. No.: **29/813,172**

(22) Filed: **Oct. 27, 2021**

(30) **Foreign Application Priority Data**

Apr. 29, 2021 (CN) 202130254168.6

(51) **LOC (14) Cl.** **14-04**

(52) **U.S. Cl.**

USPC **D14/489**

(58) **Field of Classification Search**

USPC D14/485-495

Primary Examiner — Jack Reickel

(57) **CLAIM**

The ornamental design for a display screen or portion thereof with graphical user interface, as shown and described.

DESCRIPTION

The single FIGURE is a front view of a display screen or portion thereof with a graphical user interface showing our new design.

The dash-dot broken lines in the drawings illustrate the display screen or portion thereof and form no part of the claimed design.

1 Claim, 1 Drawing Sheet
